Marguer Parker,

By her Attorneys:

Russell & Parker.

UNITED STATES PATENT OFFICE.

MORGAN PARKER, OF NEWPORT, RHODE ISLAND.

SAFETY-RAZOR.

1,830,030.

Specification of Letters Patent.

Patented Feb. 3, 1920.

Application filed November 23, 1915. Serial No. 63,082.

To all whom it may concern:
Be it known that I, MORGAN PARKER, a citizen of the United States, residing at Newport, county of Newport, and State of Rhode Island, have invented certain new and useful Improvements in Safety-Razors; and I do hereby declare the following to be a full, clear, and exact description of the invention, such as will enable others skilled in the art to which it appertains to make and use the same.

The object of the invention is to provide a safety razor of simple and inexpensive construction, having the characteristic that the blade may be easily removed and replaced, and having also the further characteristic that the safety-guard may be removed and replaced independently of the blade.

In the drawings which illustrate the preferred form of the invention, Figure 1 shows the razor with the blade and safety-guard attached; Fig. 2 shows in perspective, the end of the shank and the blade partially placed thereon, illustrating the flexing of the blade during its placement; Fig. 3 shows the end of the shank with the safety-guard in place and without the blade, the shank being viewed from the side which has the blade-retaining means; Fig. 4 shows the safety-guard removed from the shank; Fig. 5 shows the shank alone, viewed from the side which has the guard-retaining means; Fig. 6 is a cross-section on the line 6—6 of Fig. 1; Fig. 7 is a longitudinal section on the line 7—7 of Fig. 1, showing the shank, the blade and the safety-guard assembled; Fig. 8 is a longitudinal section of the blade; Fig. 9 is a longitudinal section of the shank on the line 9—9 of Fig. 5; Fig. 10 is a longitudinal section of the safety-guard on the line 10—10 of Fig. 4; Fig. 11 is a cross-section of the safety-guard on the line 11—11 of Fig. 4.

The numeral 1 indicates the handle, and the numeral 2 the shank of the razor. The blade-holding end of the shank has blade-retaining means and guard-retaining means independent of one another. The blade-retaining means on the shank comprise a pair of oppositely directed tongues 3, 4, which, in the embodiment illustrated, are stamped up from a piece of metal 5, secured, as by welding, to and slightly narrower than the blade-holding end of the shank. It will be understood, however, that the tongues 3 and 4 may be stamped up from the metal of the

shank and that the effect of the narrower portion 5 may be produced by machining the metal of the shank to form longitudinal shoulders thereon. Either of these experiments may be adopted as may happen to be the most advantageous under any particular manufacturing circumstances. The blade has a longitudinally extending slot in its central portion as shown in the drawings 6 and the end boundaries of this slot are adapted to underlie the tongues 3 and 4 as shown in Figs. 1 and 7, for example. The elevation of the tongues above the plane of the shank should be just sufficient to permit the slipping of the blade under the tongues, and the free ends of the tongues are preferably given a slight inclination toward the plane of the shank so as to have a slight spring gripping action on the blade, serving to retain the blade in position during the removal and replacement of the guard, and during the stropping operation. When the safety-guard is in place the position of the blade is further assured by the upstanding shoulders 6 on the safety-guard. From a consideration of Figs. 1, 2 and 7, it will appear that the shoulders 6 and the tongue 4 coöperate to prevent the accidental displacement of the blade 75 when in use, by reason of the fact that the blade cannot be passed out from under the tongue 4 until it has been longitudinally flexed and lifted and pulled over the shoulders 6. In other words, the tongue 4 and 80 the shoulders 6 effect a flexure of the blade during its position and until the blade has been slipped under the tongue 4 to a position such that its end will fall behind the shoulders 6, whereupon flexure of the blade 85 is relieved and it falls into the position shown in Figs. 1 and 7. To remove the blade it must be flexed again in order to clear the shoulders 6.

The safety-guard 7 has the ordinary double serrated edges, and it is adapted to be attached to and removed from the shank without disturbing the blade, in the following manner. The two serrated end portions of the guard 7 are spaced apart and united to 100 one another by arcuate straps 8 of a shape to closely embrace the shank 2 as shown in Fig. 6, and the distance between the inner opposed edges of these guard portions is slightly greater than the width of the plate 105 5 and less than the width of the shank body 2, as indicated in the drawings, so that the

- guard may be secured to the shank by slipping it on to the end of the shank with the straps 8 embracing the body of the shank 2 and the inner opposed edges of the guard 5 portions overlapping the edge shoulders formed on the shank by reason of the fact that the plate 5 is narrower than the body of the shank. For the purpose of definitely positioning the guard longitudinally on the 10 shank, the shank and the guard are provided with a coöperating recess 9 and projection 10. The recess 9 is formed in the strap which is intended to lie nearest to the handle, the other end of the guard being cut 15 away to afford a finger-grip recess permitting the easy gripping and removal of the blade without removing the guard. This end of the guard also has the shoulders 6 above referred to.
- 20 Although I prefer to incorporate the several features of improvement hereinbefore described in a single safety razor, yet it will be understood that these features are to a large extent individually useful in such 25 razors, and all or only a part of them may be employed, as may seem desirable in any particular case.

What I claim is:

1. In a razor, a shank composed of two 30 permanently united flat members of different widths forming guard retaining shoulders along the longitudinal edges of the shank, and a guard composed of two parallel flat members lying in the same plane and 35 adapted at their inner edges to rest upon the flat shoulders formed by the wider member of the shank, said members being maintained in spaced relation by transverse strap portions bent out of the plane of the flat 40 members and adapted to embrace the wider member of the shank to hold the guard in place thereon.
2. In a razor, a blade, a shank, a pair of 45 blade-holding means on the shank adapted to overlie the blade to hold it upon the shank while permitting its lengthwise movement thereon, a guard detachably mounted upon the shank, and means on the guard 50 to cause longitudinal flexure of the blade as it is moved longitudinally of the shank and then to relieve the flexure of the blade and act in conjunction with one of the blade-holding means to prevent longitudinal dis- 55 placement of the blade on the shank.
3. In a razor, a slotted blade, a shank provided with a pair of oppositely directed tongues above the plane of the shank adapted to extend through the slot in the blade and overlie the blade to hold it upon the shank while permitting longitudinal movement thereon, a guard detachably mounted upon the shank, and means on the guard to cause flexure of the blade as it is moved longitudinally of the shank and then to relieve the flexure of the blade, and act in conjunction with one of the tongues to prevent longitudinal displacement of the blade on the shank. 60
4. A safety razor having a shank, a detachable-guard, and a blade, a blade-holding means on the shank adapted to overlie a portion of the blade to hold it to the shank while permitting its lengthwise movement thereon, and means on the guard to cause longitudinal flexure of the blade as it is so moved and then to relieve the flexure of the blade and act as positioning means, requiring that the blade be flexed to effect its disengagement from the shank. 70
5. A safety razor having a shank, a removable-guard and a blade, blade-holding means on the shank adapted to overlie a portion of the blade to hold it to the shank while permitting its lengthwise movement thereon, and means on the guard to cause longitudinal flexure of the blade as it is so moved and then to relieve the flexure of the blade and act as positioning means, requiring that the blade be flexed to effect its disengagement from the shank, the said blade-holding-means having sufficient grip to hold the blade on the shank for stropping when the guard is removed. 80
6. A safety razor having a shank, a detachable-guard and a blade, blade-holding means on the shank adapted to overlie a portion of the blade to hold it to the shank while permitting its lengthwise movement thereon, and means on the guard to cause longitudinal flexure of the blade as it is so moved and then to relieve the flexure of the blade and act as positioning means requiring that the blade be flexed to effect its disengagement from the shank, the guard having a finger-grip recess to permit the easy removal of the blade. 90

In testimony whereof I affix my signature.

MORGAN PARKER.
